UNITED STATES PATENT OFFICE.

ISADORE L. LESAVOY, OF NEW YORK, N. Y.

GARMENT.

Application filed July 22, 1924. Serial No. 727,509.

My invention relates to garments, and particularly to a combination of garments for covering upper and lower portions of the body, made into a unitary structure, and the 5 method of making the same.

The object of my invention is to provide a garment which may be conveniently put on; one which readily adapts itself to movements of the body of the wearer; one where- 10 in a minimum of material and small amount of work is required in the making thereof; one adapted not only for comfortable wear, but also for assisting in supporting portions of the body; to provide a novel arrange- 15 ment of hose supporting means with said garment, and to simplify and improve generally the manufacture and form of garments of the class described.

Some of the forms which my invention 20 may take are shown in the accompanying drawing wherein Fig. 1 is a view showing two sections of material, cut from a pattern, employed in making one form of garment embodying my invention; Fig. 2 is a front 25 view of the parts of Fig. 1, in partially assembled relation; Fig. 3 is a rear view thereof; Fig. 4 is a rear view of a body garment made after the pattern of Fig. 1, and Fig. 5 is a view thereof, in side elevation, as 30 it appears upon the body of the wearer; Fig. 6 is a view similar to that of Fig. 4, but showing a modified form of garment, and Fig. 7 is an enlarged detail view of a portion 35 of the fastening means of the garment of Fig. 5.

Referring now to Fig. 1, I have shown material comprising duplicate pieces cut in a manner to permit the formation of a combined bloomer and brassière or light corslet. 40 The front edge of each piece is cut on a curved line $a-b$ and a line $b-c$. A trans- 45 verse cut $g-h$ and a vertical cut $g-i$ are made as shown. The rear edges have a straight portion $e-f$ and a curved portion $h-j$, preferably of greater length than the line $b-c$. The lower ends of the two pieces 50 are curved as shown at d and k .

When the one piece of material is joined on the line $a-b$ to the corresponding line 55 of the other piece of material, the upper or bust portion 8 of the garment is thereby formed. To form the bloomers, the pieces of material are joined on the line $b-c$ and $h-j$, respectively, and the portions $d-d$ of 60 one of the pieces 8 are sewed together and the pieces $k-k$ of the other portion joined, to

form the bloomer legs. The length of the line is much greater than that of the line $b-c$, so that when the parts are united as above explained, there will be ample room 60 in the seat of the garment and the seam ordinarily extending from one leg to the other across the crotch of the wearer will be disposed to the front of the body, and above the crotch, but this feature, in itself, 65 does not constitute a part of the present invention.

The flap portions 9 which are formed by cutting along the lines $f-g-i$ form a drop 70 seat of the garment, as shown more clearly in Figs. 4 and 5. The rear edges of the waist portion h may be provided with stiffening material and with either snap or hook fasteners, as shown at 10 in Fig. 4, while stiffening material 11 is attached to each lower 75 edge of the body portion of the garment and have eyes inserted therein for the reception of hooks carried by the seat portion 9 so that the seat portion may be fastened as shown in Figs. 5 and 7. The seat portion 80 may be provided with elastic material 12 in order to secure a snug fit at the waist- 85 line. Likewise the lower ends of the bloomer legs may be provided at 13 with elastic material. Shoulder straps 14 of any de- sired material are also provided.

The garment consisting mainly of two pieces, the amount of cutting and number of seams is reduced, thus saving in material and labor. 90

To the front seam, upon the interior of the garment, I attach hose supporters 15 that may be fastened to the stockings in the usual manner, but with the difference that they may be secured to the stockings 95 before stepping into the garment, or at least immediately after stepping into the garment and before pulling it up into position on the body. This avoids the necessity of raising the bloomer leg, after the garment is on, 100 for the purpose of attaching the supporters to the stockings as in previous constructions. By my arrangement, when the supporters are fastened and the garment drawn into place on the body, no disarrangement of the 105 clothing on the body is thereafter necessary and the supporter straps are concealed within the bloomer legs, and there is no bunching of material adjacent to the knee. Furthermore, time is saved in dressing and 110 undressing.

Referring now to Fig. 6 I show a garment

which, when completed, is substantially of the same appearance as the garment of Figs. 1 to 5 but which is made in upper and lower portions, the upper portion 8^a being made 5 separately from the lower portion 9^a and thereafter joined to the latter, by a seam at the waistline. In this arrangement the supporters 15^a are joined to the reinforcing pieces 11^a instead of to a middle seam as in 10 Fig. 4, although it will be understood that the supporters of Fig. 4 may be joined to the reinforcing pieces 11 if desired. The construction of Fig. 6 is particularly desirable 15 where different material is required as between the body portion of the garment and the bloomer portion thereof. The body portion of the garment may be made of such material that it will serve as a light corset, or it may serve as a brassière or other article 20 of apparel. The supporters extend down across, and assist in holding in the stomach of the wearer. They also assist in yieldingly positioning the garment in place on the body.

25 From the foregoing it will be seen that I provide a garment which is of simple construction, requiring comparatively few operations in the making thereof and but a relatively small amount of material, besides 30 neatly fitting the body and still permitting freedom of movement thereof. The garment is suitable for every day wear but is particularly useful as an athletic garment.

Various changes may be made without de- 35 parting from the spirit and scope of the in-

vention as defined in the accompanying claim.

Reference in the accompanying claim to upper and lower garment will be understood to refer to a brassière or similar garment 40 worn above the waistline and to a bloomer or similar garment worn below the waistline.

I claim as my invention:

A garment consisting of two sections of material that are substantially duplicates 45 and each of which has its forward edge composed of upper, lower and intermediate portions, and its rear edge also composed of upper, lower and intermediate portions, the 50 front edges of said sections being joined to one another at their upper and intermediate portions and the rear edges thereof being united at their intermediate portions, and the lower front edge portion of each section 55 being joined to the rear edge portion of said section to form legs for the garment, the intermediate rear edge portions of each section being of greater length than the intermediate front edge portions thereof, and each intermediate portion being of greater 60 width than the upper portion, and the two portions being partially separated along an approximately vertical line and along a diagonal line extending upwardly and rearwardly from said vertical line, said diagonal 65 line forming the upper edge of said intermediate portion.

In testimony whereof I, the said ISADORE L. LESAVOY, have hereunto set my hand.

ISADORE L. LESAVOY!
